UNITED STATES PATENT OFFICE.

RICHARD H. WELLES, OF KENOSHA, WISCONSIN, ASSIGNOR TO THE BADGER BRASS MFG. CO., OF KENOSHA, WISCONSIN, A CORPORATION OF WISCONSIN.

CONNECTOR-SOCKET FOR ELECTRIC LAMPS OR THE LIKE.

1,221,255.

Specification of Letters Patent. Patented Apr. 3, 1917.

Application filed May 19, 1916. Serial No. 98,498.

To all whom it may concern:

Be it known that I, RICHARD H. WELLES, a citizen of the United States, residing at Kenosha, in the county of Kenosha and State of Wisconsin, have invented certain new and useful Improvements in Connector-Sockets for Electric Lamps or the like, of which the following is a specification.

My invention relates to improvements in connector sockets, and is well fitted for use in connection with electric lighting devices, for instance, electrical vehicle lamps.

The objects of the invention are, to provide a connector socket of the bayonet type, constructed of a comparatively small number of mechanical parts; to provide a construction in which the parts used are comparatively simple in design and also particularly economical to manufacture in large quantities by modern factory methods; to provide a socket of the bayonet type to which the electrical contacting means may be connected rapidly and efficiently; to provide a construction in which the electrical contact is efficient and positive under all conditions; to provide a construction in which danger of short-circuiting is reduced to a minimum; to provide a construction which is particularly well fitted for use in connection with automobile search lamps of the single-wire type in which the lamp filament must be capable of axial movement in the lamp; and, in general, to provide an improved construction of the character referred to.

In the drawings I have illustrated my improved socket as applied to an automobile search lamp of the single-wire type with adjustable bulb for focusing purposes. In said drawings—

Figure 1 is a fragmentary section taken through the axis of the search lamp;

Fig. 2 shows the socket removed from its support in the lamp;

Fig. 3 is a section taken on the line 3—3 of Fig. 1; and

Fig. 4 is a section taken on the line 4—4 of Fig. 1.

Referring to the drawings, the socket illustrated, which is of the bayonet type, comprises, as the principal element, a tubular shell or sleeve 10 having the usual pair of opposed bayonet slots 11 which co-operate with the locking pins 12 of an Edi-

swan base 13 supporting the lamp bulb 14. 55 The rear end of the shell 10 is open but is formed with a turnover flange 15 projecting inwardly a sufficient distance to form a shoulder for the coil spring 16 located within the hollow shell 10. 60

As best shown in Fig. 2, a rectangular slot 17 is cut in the side of the shell 10, wide enough to accommodate a pair of plates 18 and 19 made out of fiber or other suitable insulating material. As shown in Fig. 3, 65 the inner ends of said insulating plates 18 and 19 are circular in shape so as to fit within the bore of the shell 10, and have extensions 20 which project through the said slot 17 of the shell. Between said plates 70 18 and 19 I insert a connector 21 and secure the said three parts together by means of a central rivet 22. Said rivet 22 is formed at its outer end with a rounded fillister head 23 which engages the contact plate 75 24 on the lamp base 13. Beneath the head 23 the rivet is of large diameter, having a shoulder which engages the surface of the connector 21, the neck 25 of the rivet extending through perforations in the connector 21 80 and the plate 18. The end of the neck 25 of the rivet is headed into a countersunk small diameter washer 26 which holds the rivet and associated parts together.

In order to facilitate attachment of the 85 electrical conductor to the connector 21, the latter is perforated, as shown at 27, and formed with a plurality of ears, as at 28 and 29, which may be folded over the connecting wire for additional security. The connector 90 21 is also preferably constructed so as to provide a pair of opposed lateral extensions 30 and 31, the outer ends of which are bent over the edges of the plates 18 and 19, respectively, in opposite directions, as shown 95 in Fig. 2, thereby effectually preventing angular movement of the connector and possible short-circuiting. It will be observed that the washer 26 is of relatively small diameter compared with the diameter of the 100 spring 16 so that there is no possible danger of said washer and spring accidentally making contact with each other. The coil spring 16 of course is of the compression type and exerts enough pressure on the plate 18 to 105 insure proper contact between the head 23 and the contact plate 24, while at the same time locking the Ediswan base in the socket.

It will be seen that my improved socket is of exceedingly simple design, while at the same time it is extremely positive and reliable in operation. The spring 16 may be 5 made heavy enough to insure a firm and reliable contact between the contact button 23 and the contact plate 24 on the base of the lamp or other connective device. The construction also allows ample insulation for 10 the parts which are electrically connected to the circuit, the insulating plates 18 and 19 maintaining the contact button away from the grounded shell and spring, while the extensions 20 of the said plates 18 and 19 prevent 15 the connector 21 from grounding on the sides or ends of the slots 17.

Although the invention is capable of many applications, I have shown in Fig. 1 as a particular application of my invention, a 20 section of an electrical search lamp of the focusing type. In said lamp, 32 represents a portion of the outer casing within which is nested a parabolic reflector 33. Arranged coaxially within the lamp casing and secured 25 thereto by a flanged member 34, I mount a supporting tube or sleeve 35 extending toward the front of the lamp. The front end of said tube 35 is open so as to admit the socket shell 10 which is slidable therein, the 30 tube 35 being slotted or cut away, as shown at 36, in order to accommodate the projecting insulating plates 18 and 19. Axial adjustment of the socket for focusing the filament 37 is effected by means of an adjusting 35 screw 38 arranged parallel with the axis of the tube 35 and coöperating with a tapped aperture in the angle piece 39 secured to the socket shell 10 in any suitable manner, as by a screw 40. The head 41 of the screw 38 40 projects through an aperture in the outer casing 32, the neck of the screw being rotatably supported in the flanged member 34. Axial movement of the screw 38 is prevented 45 by means of a fixed collar 42. It should be understood that the slot 36 is extended rearwardly a sufficient distance to provide for the maximum rearward movement of the angle piece 39 when adjusting the focus.

The construction herein described possesses 50 many advantages over devices of this character which have been heretofore brought to my attention. In the first place, the parts of the device are exceptionally cheap and simple to produce by means of 55 automatic machinery, such as punch presses and screw machines. Also, the various parts of the socket may be assembled together swiftly and accurately with a minimum of trouble and without the danger of injuring 60 or impairing the efficiency of any part or parts of the structure. In practice, when assembling the device, the large spring 16 and the shell 22 are assembled together by simply slipping the spring endwise into the tube 65 from the front. The front end of the spring

is then drawn rearwardly into compressed relation by means of any suitable tool inserted from the rear of the shell and the insulating plates, connector, and rivet, which have previously been united together in a 70 unitary structure are inserted through the side slot 17. When inserting the last named assembled member through the slot 17, the plates are of course twisted so that they will 75 enter the slot diagonally.

One of the principal advantages of the device is the ease with which it may be connected to the source of supply. In other 80 sockets, it is usually necessary to lead the supply conductor into the interior of the socket and there secure the same to the contact or other conducting part by means of a 85 screw or soldering. Soldering the wire inside the socket is of course open to many objections, and usually cannot be practised except by a skilled mechanic, without danger of injuring the insulation or establishing a short circuit. In my improved socket, the 90 connecting clip 27 extends outwardly from the shell a considerable distance and the wire may be secured to its projecting end by soldering without danger of short circuits or destruction of the insulation.

Since the described details of construction 95 may be modified considerably to suit individual tastes or requirements, it should be understood that the scope of the invention is not limited thereby but must be determined by reference to the appended claims.

I claim—

1. In a socket of the class described, the combination of a tubular shell having an aperture in its side and intermediate its ends, the front end of said shell being arranged to receive an Ediswan base, a plate 105 of insulating material transversely arranged in and slidable in said shell, said plate having an integral extension projecting through said aperture to prevent angular movement of said plate, a contact carried by said plate 110 for engaging said base, a spring in said shell behind said plate for forcing said contact into engagement with said base, and a connecting clip extending from said contact outwardly through said aperture and locked 115 against angular movement with reference to said plate.

2. In a socket of the class described, the combination of a tubular shell provided at its front end with means for locking a base 120 inserted in said socket, said shell having intermediate its ends a side aperture, a plate 125 of insulating material arranged transversely in and slidable in said shell, a contact carried by said plate for engaging said base, a coil spring in the rear of said shell for forcing said contact toward said base, insulating means between said spring and said contact, and an electrical connecting clip extending through said aperture into said 130

shell and permanently united to said contact, said plate, contact, and clip constituting an integral structure.

3. In a socket of the class described, the combination of a tubular shell provided at its front end with bayonet slots for locking an Ediswan base inserted in said socket, said shell having intermediate its ends an aperture in its side, a plate of insulating material arranged transversely in said shell, substantially filling the cross-section of said shell and having an integral extension projecting through said aperture, a contact carried by said plate for engaging said base, a coil spring of comparatively large diameter substantially filling the cross-section of said shell at the rear of said plate, having its rear end positioned in said shell and having its front end engaging said plate to force said contact into engagement with said base, and a connecting clip extending outwardly from said contact through said aperture and locked to said plate against relative angular movement.
- 25 4. In a socket of the class described, the combination of a shell having bayonet slots at its front end and a longitudinal slot in its side intermediate its ends, the rear end of said tube being flanged inwardly, an Ediswan base in the front end of said shell, a pair of plates of insulating material transversely disposed in said shell, one of said plates substantially filling the cross-section of said shell, and both of said plates having integral extensions projecting outwardly through said slot, a contact rivet carried centrally by said plates and uniting the same together, a coil compression spring of comparatively large diameter in the rear end of said shell, its external diameter being sufficient to substantially fill the interior of said shell, the rear end of said spring being positioned by said flange, and its front end engaging one of said plates to force said contact toward said base, and a connector

interposed between said plates extending outwardly from said contact through said slot and locked to said plates to prevent relative transverse angular movement of said plates and said connector.

5. In a socket of the class described, the combination of a shell having bayonet slots at its front end and a longitudinal slot in its side intermediate its ends, an Ediswan base in the front end of said shell, a front plate of insulating material transversely disposed in said shell, slideable therein, and having an integral extension projecting outwardly through said slot, a rear insulating plate, a spring in the rear end of said shell engaging said rear plate and tending to force the same toward the base, an electrical connecting clip interposed between said plates and having an integral extension extending through said aperture, and a contact rivet extending through said first plate and said connecting clip and uniting the same permanently together and adapted to engage said base.

- 20 6. In a socket of the class described, the combination of a tubular shell having an aperture in its side intermediate its ends, the front end of said shell being arranged to receive an Ediswan base, a plate of insulating material transversely arranged in said shell and slideable in said shell, said plate having an extension projecting through said aperture to limit angular movement of said plate, a connecting clip at the rear of said plate and locked thereto against relative angular movement and extending from out of the shell through said aperture, a second insulating plate arranged at the rear of said clip, a spring engaging said last named plate and tending to force said plates toward the base, and a contact pin carried by said plate, engaging, and permanently united to, said clip for securing said plates together.

RICHARD H. WELLES.
